UNITED STATES PATENT OFFICE.

PETER KUZMJAK, OF NEW YORK, N. Y.

DESIGN FOR A PAIR OF TONGS.

• 57,289.

Specification for Design.

Patented Mar. 8, 1921.

Application filed June 11, 1920. Serial No. 388,362. Term of patent 7 years.

To all whom it may concern:

Be it known that I, PETER KUZMJAK, a citizen of Czecho-Slovakia, residing at New York, in the county of New York and State of New York, have invented a new, original and ornamental Design for a Pair of Tongs, of which the following is a specification, reference being had to the accompanying drawing, forming part thereof.

The figure is a view in perspective of a pair of tongs, showing my new design.

I claim:

The ornamental design for a pair of tongs, as shown.

PETER KUZMJAK.
